METHOD OF TREATING HUMAN HAIR

Ralph Mauriell, Oceanport, N. J., assignor of one-half to Tadeusz P. Titus, Cleveland, Ohio.

Application July 1, 1938, Serial No. 217,025

16 Claims. (Cl. 132—1)

My invention relates to a method of treating, waving and improving human hair and to promoting a healthy scalp condition and has for one of the principal objects thereof the provision of such a method wherein hair is subjected to an operation which produces a high degree of pliability therein, thereby enabling the hair to be readily and quickly waved and set in a manner to effect a maximum degree of permanency of the hair so waved.

Another object of my invention is to provide a method of the above described character wherein the hair is placed in a highly receptive condition for receiving and absorbing medicaments and the like for promoting a lustrous growth thereof.

A further object of my invention is to provide a method of the above described character wherein moisture from the atmosphere may readily penetrate the hair and thus assist in maintaining the wave therein and at the same time promote a healthy scalp condition.

Other objects and advantages will be apparent from the following description, appended claims and annexed drawing.

Referring to the drawing wherein like reference characters designate like parts throughout the several views:

Figure 1 illustrates an initial step in my method of treating human hair.

Figure 2 is a detail greatly enlarged perspective view of a section of a strand of hair, the latter having been subjected to one of the operations of my method.

As illustrated in Figure 2 of the drawing, strands of human hair are made up of a number of layers, the central or inner layers 5 being known as the medulla, which are surrounded with intermediate layers 6 known as the cortex and also with outer protective layers 7 of a relative hardness or stiffness known as the cuticle.

The cuticle comprises imbricated scales 8 having their outer edges 9 extending in a direction away from the scalp of the head. The cuticle not only serves to conceal and protect the cortex but also the underlying follicles.

Ordinarily, when hair is treated, the cuticle due to its semi-rigid condition prevents to a large extent impregnation of medicaments and the like to the cortex and medulla thereby nullifying to a large degree the beneficial treatments the medicaments would ordinarily produce. Also, due to said semi-rigid condition of the cuticle, the hair has a tendency to resist

waving or curling and to render any waving or curling of a short duration.

My method overcomes the foregoing disadvantages in treating the human hair and comprises subjecting growing hair to a moistening operation by applying thereto a liquid, for instance water, which acts to soften the cuticle. When the cuticle has thus been softened, a section 10 of the hair (as illustrated in Figure 1) 10 is grasped between the fingers of one hand and held in a relatively taut condition between the fingers and scalp. When thus positioned, a relatively sharp instrument, for instance a scissor blade 11, is moved over the section 10 and in a 15 direction towards the head to effect scarification of the section and removing therefrom portions of the cuticle to expose the cortex, as illustrated in Figure 2.

When the cuticle has thus been removed and 20 the cortex exposed with the fibers of the latter intermixed with the fibers of the original tissue, the shape of the hair may be readily changed to effect waving due to the high degree of pliability thereof brought about by the removal of 25 the cuticle.

The hair in this condition is treated with 30 medicaments which are readily absorbed through the cortex thereby stimulating the growth of the hair. Hair thus curled or waved is impregnated with water and the wave set in a neat and desired style at room temperature, that is, a temperature within the range of 65° to 70° F. approximately. Due to the quick absorption of the water by the cortex layers, the hair will dry in a minimum 35 length of time and thus eliminate the ordinary drying treatments. Also, the ready absorption of moisture from the atmosphere by the cortex layers serves to retain the hair in a wavy condition.

40 From the foregoing it will be apparent that I have provided a method for treating hair wherein the same may be readily and quickly waved and set with a high degree of permanency.

What I claim is:

45 1. A method of treating hair consisting of removing cuticle from said hair and of fashioning said hair into a wave.

2. A method of treating hair consisting of subjecting hair to a scarifying operation to remove 50 the cuticle therefrom, of impregnating said scarified hair with a liquid, and of setting said impregnated hair to form a wave.

3. A method of treating human hair consisting of applying a softening agent to said hair to effect a softening thereof, of subjecting said hair

to a scarifying operation to remove the cuticle therefrom, and of impregnating said scarified hair with a liquid to effect a setting thereof.

4. A method of treating human hair consisting of subjecting hair to a scarifying operation to remove the cuticle therefrom to obtain maximum pliability of said hair, of subjecting said scarified hair to a curling operation to form a wave, and of impregnating said waved hair with a liquid to effect a setting of said wave.

5. A method of treating human hair consisting of applying a softening agent to said hair to effect a softening thereof, of subjecting said hair to a scarifying operation to remove the cuticle therefrom to obtain maximum pliability of said hair, of subjecting said scarified hair to a curling operation to form a wave, and of impregnating said wave with a liquid to effect a setting thereof.

6. Process of treating human hair comprising softening the hair cuticle and, by scraping, removing a segmental area of the cuticle for facilitating introduction of substances directly to the cortex.

7. The step in a process for waving human hair which comprises scraping the cuticle of the hair to remove said cuticle exposing the cortex, over a segmental area.

8. Method of treating human hair to facilitate direct application of substances to the cortex which comprises removing portions of the cuticle by scraping.

9. Method of treating human hair comprising scraping segmental areas of cuticle from strands of softened hair to expose the hair cortex and impregnating said hair cortex with fluid materials.

10. The step in the method of waving human hair which comprises removing a portion of the cuticle from individual hairs.

11. The steps in the method of waving human hair which comprise removing a portion of the cuticle from individual hairs and forming the hair into a wave formation.

5 12. The method of waving human hair which comprises removing a portion of the cuticle from individual hairs and forming individual hairs into wave formation with the hairs in a moist state.

10 13. The method of waving human hair which comprises removing a portion of the cuticle from human hairs and forming the hairs into wave formation while the hairs are in a moist state and at a temperature within the range of 65° to 70° F. approximately.

15 14. The method of waving human hair which comprises removing a portion of the cuticle from individual hairs, moistening the hairs and forming the hairs into a wave formation while they are in a moist state and at a temperature within the range of 65° to 70° F. approximately.

20 15. The method of waving human hair which comprises parting the hair to separate a lock, scraping the underside of the lock to remove a portion of the cuticle from a substantial number of individual hairs in the lock, and forming the lock into a wave formation while in a moist state and at a temperature within the range of 65° to 70° F. approximately.

25 16. The method of waving human hair on the head which comprises moistening the hair, parting the hair to separate a lock, scraping the lock over an area spaced from the end thereof to remove a portion of the cuticle from a substantial number of individual hairs in the lock and forming the lock into a wave formation while the hair is in a moist state and at a temperature within the range of 65° to 70° F. approximately.
